UNITED STATES PATENT OFFICE.

RICHARD J. GREENWAY, OF WESTERLY, RHODE ISLAND, ASSIGNOR TO C. B. COTTRELL & SONS COMPANY, OF STONINGTON, CONNECTICUT, A CORPORATION OF DELAWARE.

ENDLESS-BELT MOUNTING.

Application filed March 3, 1925. Serial No. 12,848.

In a machine using an endless belt of felt, pile fabric or the like, for conveying an anti-offset material, such as talc, to the freshly printed sides of sheets or webs or to the surfaces of cylinders which come in contact with such freshly printed sides, I have found that it is very desirable that means should be employed for easily and quickly dismounting and mounting the belt rolls to permit the ready removal and replacement of the belt without undue strain on said belt which would be liable to tear or distort it.

A practical embodiment of my invention is represented in the accompanying drawings, in which—

Fig. 1 represents in detail top plan that portion of a printing press which includes the offset material applying belt and the means for removably mounting its rolls.

Fig. 2 represents a section taken in the plane of the line II—II of Fig. 1, looking in the direction of the arrows.

The endless belt for applying the anti-offset material to the freshly printed side of the sheet or web or to the surface of the cylinder which comes in contact therewith, is denoted by 1. This endless belt passes around the drive roll 2 and a plurality of free rolls, all removably mounted in the auxiliary frame 3, as will be immediately described. In the present instance I have shown three of these free rolls 4, 5 and 6, the roll 4 being a belt tightening roll for properly adjusting the tension of the endless belt after it has been placed in position on its rolls.

The portion of the belt between the free rolls 5 and 6 is adapted to contact with the freshly printed side of the sheet or web (not shown herein) as it passes around the cylinder 7, or with the surface of the cylinder itself, as the case may be.

The means which I have shown for removably mounting the belt rolls in the auxiliary frame is constructed, arranged and operated as follows:

The ends of the drive roll shaft 8 are mounted in journal bearings carried by the auxiliary frame, the upper half 9 of each bearing being fixed and its lower half 10 being hinged. The free end of the lower half bearing 10 is removably secured in its closed position to complete the bearing, by the usual bolt and nut device 11, 12. This arrangement permits the drive roll 2 to be

readily dropped out of its mounting and removed, when the lower half bearing 10 is opened.

Each of the free rolls 4, 5 and 6 is mounted on anti-friction bearings 13 at the inner ends of stud axles 14 projecting inwardly from the sides of the auxiliary frame into the ends of their respective rolls. For permitting the ready mounting and dismounting of these free rolls, the stud axles 14 have an endwise movement in the sides of the auxiliary frame 3, as, for instance, by providing screw-threaded engagements between these stud axles and the sides of the auxiliary frame. This will permit the stud axles to be moved into and out of the inner members of the anti-friction bearings.

From the above description it will be seen that if the endless belt is to be removed, the drive roll and the free rolls may be almost instantly detached from their mountings and removed to a point where the belt may be readily taken off therefrom. The same belt or another belt may be readily replaced on these rolls and the rolls then remounted in the auxiliary frame. The belt tightener roll 4 may then be adjusted by the usual devices 15, 16, for bringing the endless belt into the proper tension.

It will furthermore be seen that, by mounting the free rolls on anti-friction bearings, the endless belt may be driven by the drive roll with a minimum amount of strain on the belt. This is very important where the belt is composed of felt, pile fabric or the like, which becomes very easily distorted or torn.

It is evident that various changes may be resorted to in the construction, form and arrangement of the several parts without departing from the spirit and scope of my invention; hence, I do not intend to limit myself to the particular embodiment herein shown and described, but

What I claim is:—

1. A frame, an endless belt, its driving and free rolls, and means for easily and quickly dismounting and mounting the rolls to permit the ready removal and replacement of the belt, said means comprising openable journal bearings for the driving roll shaft and withdrawable stud axles for the free rolls.

2. A frame, an endless belt, its driving and free rolls, and means for easily and

quickly dismounting and mounting the rolls to permit the ready removal and replacement of the belt, said means comprising openable journal bearings for the driving roll shaft and withdrawable stud axles for the free rolls, and anti-friction bearings located between the free rolls and their stud axles.

3. A frame, an endless belt, its driving and free rolls, and means for dismounting and mounting the rolls to permit the removal and replacement of the belt, comprising openable journal bearings for the driving roll shaft and stud axles for the free rolls, said stud axles being mounted for end-wise movement in the frame to permit their withdrawal from and insertion into the ends of their respective free rolls.

4. A frame, an endless belt, its driving and free rolls, and means for dismounting and mounting the rolls to permit the removal and replacement of the belt, comprising openable journal bearings for the drive roll shaft and stud axles for the free rolls having screw-threaded engagements with the frame to permit their withdrawal from and insertion into the ends of their respective free rolls.

5. A frame, an endless belt, its driving and free rolls, and means for dismounting and mounting the rolls to permit the removal and replacement of the belt, comprising openable journal bearings for the driving roll shaft and stud axles for the free rolls, said stud axles being mounted for end-wise movement in the frame to permit their withdrawal from and insertion into the ends of their respective free rolls, and anti-friction bearings located between the free rolls and their stud axles.

6. A frame, an endless belt, its driving and free rolls, and means for dismounting and mounting the rolls to permit the removal and replacement of the belt, comprising openable journal bearings for the drive roll shaft and stud axles for the free rolls having screw-threaded engagements with the frame to permit their withdrawal from and insertion into the ends of their respective free rolls, and anti-friction bearings located between the free rolls and their stud axles.

In testimony, that I claim the foregoing as my invention, I have signed my name this 27th day of February A D 1925.

RICHARD J. GREENWAY.
